UNITED STATES PATENT OFFICE

AUGUST DE FREITAS, OF HONOLULU, TERRITORY OF HAWAII

PORTABLE LUNCH CARRIER

Application filed April 3, 1930. Serial No. 441,324.

My invention relates to portable lunch carriers and an object of the same is to provide a compact device of this character which can be conveniently handled and transported by ⁵ picnickers, autoists, etc.

A further object of the invention is to provide a lunch carrier embodying a casing or receptacle and a plurality of small food containing receptacles as well as knives, forks ¹⁰ and other eating utensils.

Still another object of the invention is to provide a portable lunch carrier embodying a detachable base which may be readily removed from the receptacle and utilized as a ¹⁵ stove.

An additional object of the invention is to provide a device of this character embodying a vertical tie rod, a cylindrical casing whose walls are held together by the tie rod and ²⁰ which is equipped with a plurality of article supporting brackets, which are held in assembled relation by the vertical tie rod.

With the preceding and other objects and advantages in mind, the invention consists in ²⁵ the novel combination of elements, constructions and arrangements of parts and operations to be hereinafter more fully described, claimed and illustrated in the accompanying drawings, wherein:

³⁰ Figure 1 is a perspective of my improved portable lunch carrier;

Fig. 2 is an elevation of the same with the doors swung open to illustrate the interior of the carrier;

³⁵ Fig. 3 is a top plan view of the removable face or stove detached from the carrier;

Fig. 4 is a vertical sectional view of the invention;

Fig. 5 is a horizontal section taken on the ⁴⁰ line 5-5 of Fig. 4; and

Fig. 6 is a perspective of one of the brackets embodied in the invention.

Referring to the invention in detail a base or stove is provided which consists of ⁴⁵ a pair of parallel inverted substantially U-shaped members 5 terminating in laterally extending supporting feet 6 and tied together by cross bars 7 which are suitably secured to the horizontal parts of the members 5. An annulus or ring 8 is secured to

the horizontal parts of the members 5 by suitable fastenings 9. The inverted U-shaped members are braced by horizontally extending brace members or bars 10 which are riveted or otherwise secured to the vertical legs ⁵⁵ of the members 5 as at 11.

A rectangular water reservoir 12 is provided and attached to one pair of its side walls are hooks 13 which engage the upper edges of the adjacent bars 10 to removably ⁶⁰ support the reservoir within the confines of the inverted U-shaped member. A filling plug 14 is provided in the top wall of the reservoir and a suitable valve 15 is provided for controlling the outlet of the water from ⁶⁵ the reservoir.

A cylindrical casing or cabinet is provided and consists of a circular bottom plate 16 which rests upon the ring or annulus 8 and is detachably secured thereto by removable ⁷⁰ fastenings 17. Arising from the circular plate 16 at diametrically opposite points and at the outer edge of the plate is a pair of vertically extending bars 18 which terminate in inwardly directed extensions 19. ⁷⁵ The extensions 19 at the lower ends of the bars 18 are secured to the bottom disk 16 by suitable fastenings 20. An upper circular plate or disk 21 is arranged above the disk 16 and is secured to the extensions 19 at the ⁸⁰ upper ends of the bars 18 by fastenings 22.

Arranged between the disks 16 and 21 is a pair of semi-circular wall sections or doors 23. The edges of the sections 23 are arranged contiguous with the edges of one of the bars 18 and are connected thereto by suitable hinges 24. Angle brackets 19a are secured to the circular plates 16 and 21 adjacent their outer edges and are arranged in vertically aligned pairs as disclosed in Fig. ⁸⁵ 4 so as to limit the closing movement of the sections or doors 23 and hold them in the proper relation to the outer edges of the plates 16 and 21. Normally the free edges of the doors or sections overlap the other vertical bar 18 as disclosed in Fig. 5. A hasp ⁹⁰ 25 is carried by the free edge of one of the doors or sections and is engageable with a suitable hasp 26 carried by the free ends of the other section or door. If desired a con- ⁹⁵ 190

ventional lock, not shown, may be engaged with the staple to lock the doors against being opened. A cylindrical column 27 is interposed between the circular plates at their centers. The upper end of the column receives a depending annular flange 28 carried by the plate 21, while the lower end of the column is received on an upstanding sleeve 28^a concentric with the annular flange 28 and attached to the circular plate 16.

10 A vertical tie rod 29 extends centrally through the column 27 and the circular plates 16 and 21. A nut 30 is threaded on the lower end of the tie rod and bears against the under face of the plate 16. A U-shaped yoke 31 is received on the upper end of the tie rod and contacts with the plate 21. A nut 32 is threaded upon the upper end of the tie rod and bears against the U-shaped yoke to hold the latter and the plate 21 against vertical displacement. Secured between the arms of the U-shaped yoke is a suitable hand grip 33 whereby the carrier is handled.

15 A plurality of metallic receptacles 34 such as food containers, coffee pot, etc., are supported from the vertical column 27. For this purpose a plurality of brackets such as disclosed in Fig. 6 is provided. Each bracket consists of a longitudinal bar or arm 35 having an off-set extension 36 at one end and which is provided with a circular opening 37. A bar 38 extends at right angles to the arm 35 and is secured thereto by a rivet 39. The arm terminates in upstanding tongues 35^a which extend through U-shaped members 34^a attached to each receptacle at diametrically opposite points. The column 27 is provided with a plurality of sets of radially disposed slots along its length through which the extensions 36 pass. As shown in Fig. 4 the openings 37 of the extensions 36 are in registration and receive the tie rod 29. Thus the tie rod in addition to tying the disks 16 and 21 together serves to hold the brackets in place.

20 Clamps 41 are secured to the bottom disk 16 and hold certain of the receptacles 34. As shown in Fig. 2 dining utensils 42 are supported from the doors or sections 23 by clips 43 attached to the inner face of these parts. Also a holder 44 is attached to one of these doors for holding a tooth pick holder 45. With the receptacles thus supported on the brackets they will be effectively held and may be readily disengaged therefrom.

25 In the event it is desired to cook the food the stove or base may be detached from the plate 16 by removal of the fastening 17. The tank 12 will be removed and a suitable heater 18 arranged beneath the stove.

30 Legs 46 are attached to the underface of the disk 16 for supporting the carrier when the stove is detached.

What I claim is:

35 1. In combination a cabinet, a tubular

member extending vertically therein, a plurality of article supporting brackets radiating from the tubular member and having their inner ends extended through the walls of the tubular member, and a rod extending through the tubular member and engaged with the ends of the brackets to hold them in place. 70

2. In combination a tubular column, a plurality of article supporting brackets extending therefrom and having their inner ends extended through the walls of the tubular column and provided with registering openings, and a rod extending vertically through the column and passing through the openings to hold the brackets in place. 75

3. A receptacle having end plates, a tubular member interposed between the end plates and having a plurality of slots therein, brackets arranged adjacent the column and having extensions which pass through the slots and provided with registering openings, and a tie rod passing through the registering openings and end plates to tie the latter together and hold the brackets in place. 80 85

4. A receptacle having end plates, a tubular member interposed between the end plates and having a plurality of slots therein, brackets arranged adjacent the column and having extensions which pass through the slots and provided with registering openings, and a tie rod passing through the registering openings and end plates to tie the latter together and hold the brackets in place, and a handle member secured to one end of the tie rod. 90 95

5. In a portable lunch carrier a pair of spaced horizontal plates, a hollow column having its ends engaging the plates, a tie rod passing through the columns and engaged with the plates, and hinged side walls arranged at the edges of the parallel plates. 100
